EDWIN A. GASKILL AND JOSEPH FRANKLIN GASKILL, OF LANEVILLE, WEST VIRGINIA.

SPAR-CAP.

1,072,845.

Specification of Letters Patent. Patented Sept. 9, 1913.

Original application filed March 25, 1912, Serial No. 686,183. Divided and this application filed June 13, 1912. Serial No. 703,506.

To all whom it may concern:

Be it known that we, EDWIN A. GASKILL and JOSEPH FRANKLIN GASKILL, citizens of the United States, residing at Laneville, in 5 the county of Tucker and State of West Virginia, have jointly invented a certain new and useful Improved Spar-Cap, of which the following is a specification.

This invention relates to apparatus used 10 in connection with the skidding of logs and has more particular relation to the providing of a novel spar cap for use in conjunction with a spar and spar base in the over-head skidding of logs as set forth in our application for Letters Patent, Serial No. 686,183, of which this case is a division.

The principal object of the present invention is to provide a novel construction of 20 spar cap for use in conjunction with a spar and spar base, whereby simplicity, efficiency and cheapness in the over-head skidding of logs is effected.

A further object of the present invention is to provide a spar cap of such construction 25 that when its complemental spar and spar base are in working position, the spar together with the spar cap, may be readily moved around its own axis, to properly aline the sheaves carried by the spar cap, without 30 interfering with the guy rods used in positioning the spar.

A further object of the present invention is to provide a spar cap equipped with a 35 series of sheaves, the sheaves being so arranged that they are contained wholly within the spar supporting the cap.

Still further objects of the present invention relate to the providing of general 40 details of construction and arrangement of parts.

With these and other objects in view, the invention consists of the improvements hereinafter described and finally claimed.

The nature, characteristic features and 45 scope of the invention will be more fully understood from the following description, taken in connection with the accompanying drawing, forming part hereof and in which:

Figure 1, is a view in elevation of a tubular spar, equipped with a spar cap embodying the invention, Fig. 2, is a view in elevation of the spar cap detached from its complemental spar, Fig. 3, is a view in sec-

tion taken upon the line 3—3 of Fig. 2, Fig. 4, is a view of the underside of the spar cap 55 shown in the foregoing figures, Fig. 5, is a plan view of the guy ring shown in Fig. 1, and Fig. 6, is a plan view of the split ring shown in Fig. 1.

The spar cap of the invention is particularly adapted for use in connection with the spar shown and described in our above mentioned application for Letters Patent, which spar is adapted for use in the over-head skidding of logs at the place where the trees 65 are felled or cut down. Referring now more particularly to Fig. 1, such spar is designated 10, and is shown as being of tubular formation and of generally lattice-like or skeleton construction. As this spar forms 70 no part of the present invention, the same being claimed in our above mentioned application for Letters Patent, further description of this spar is unnecessary. This spar 10, is provided at its top with a spar cap 11, 75 see Figs. 1, 2, 3, and 4. As clearly shown in said figures, the spar cap comprises a generally ring-like member 12, terminating at its top in an upwardly extending ring-like portion 13, having a closed top 14. The 80 ring-like portion 13, is slightly smaller in diameter than is the ring-like portion 12. As clearly shown in Fig. 3, the base of the part 12, is open. In practice and as shown in Fig. 1, the uprights of the spar 10, may be 85 secured to the ring-like portion 12.

Arranged centrally of the ring 12, and extended thereacross and preferably formed integral therewith, are spaced plates 30, 90 each plate having a horizontally extending foot 15. Each foot 15, is provided with a semi-circular face 16. In practice, these semi-circular faces 16, provide convenient parts to which the spar uprights may be bolted. Journaled between the plates 30, 95 are sheaves 17, 18, and 19. The sheave 17, is arranged in a plane below that of the sheaves 18, and 19. The sheaves 18, and 19, are arranged opposite to one another and are in the same plane. That portion of the 100 ring 12, adjacent the sheaves 18, and 19, is cut-away as at 20, to permit of the passage therethrough of a main line cable (not shown in the drawings). Adapted to be fitted around the part 13, is a guy ring 21. 105 This guy ring rests upon the ledge 22,

formed by the parts 12, and 13, and is retained in position by means of a split ring 23, bolted as at 24, to the part 13, of the spar cap. Guy ropes 31, connect with the 5 guy ring 21, see Fig. 1, and serve to properly position the spar 10. It will thus be apparent that the spar 10, and spar cap 11, are positively secured together and may be moved around their own axes without interfering with the guy ring and guy ropes which latter parts are relatively fixed with respect to the spar and spar cap. It may be stated at this time that the sheaves 17, 10 18, and 19, in effect form part of the spar 15 and are contained wholly within the same. Thus, the sheaves may be properly aligned with desired objects readily and expeditiously and without interfering in any way with the guy ring or guy ropes. It may be 20 stated also at this time that the closed top 14, of the spar cap, serves to a degree to protect the sheaves from inclement weather. The ring 12, has depending from its underside, ears 25, suspended from which are sections of chains, ropes or the like 26, see 25 Fig. 1, rings 27, provided with eyes 28, being present between the sections of chains, ropes or the like 26. In practice, it is sometimes convenient to use pulley blocks 30 in conjunction with the spar 10, and in this connection it may be remarked that ropes, chains or the like, may be passed through the rings 27, and around the spar 10, to which ropes, chains or the like, pulley blocks 35 may be secured.

What we claim is:

1. A spar cap for tubular spars comprising a top plate provided with a depending centrally disposed forked portion and an 40 upwardly extending guy ring receiving element, a guy ring and a sheave journaled within said depending forked portion said sheave being adapted to be contained wholly within the tubular spar.
- 45 2. A spar cap comprising an inverted generally dish-shaped plate, centrally disposed spaced plates depending from the first mentioned plate and a sheave journaled between said spaced plates.
- 50 3. A spar cap comprising an inverted generally dish-shaped plate, centrally disposed spaced plates arranged in parallelism depending from the first mentioned plate each of said spaced plates terminating in a hori-

zontally disposed foot portion and a sheave 55 journaled between said spaced plates.

4. A spar cap comprising an inverted generally dish-shaped plate provided with a guy ring receiving ledge, a guy ring, a split ring for retaining said guy ring in position upon said ledge, centrally disposed spaced plates arranged in parallelism depending from the first mentioned plate each spaced plate terminating in a horizontally disposed foot portion having a curved outer 60 65 face and a sheave journaled between said spaced plates.

5. A spar cap the top portion of which has depending therefrom a series of short chain sections, ropes or the like, ring-like 70 mediums being present between adjacent sections of chains, ropes or the like.

6. A spar cap comprising a top plate, ears depending from said plate and a series of short chain sections, ropes or the like 75 suspended from said ears, rings being present between adjacent sections of chains, ropes or the like.

7. A spar cap comprising a top portion provided with depending spaced plates arranged in parallelism each plate terminating in a horizontally disposed foot whereof the spaced plates form a sheave receiving element and the feet form means for spar attachment. 80

8. In combination a tubular spar, a cap comprising an inverted generally dish-shaped top piece provided interiorly with a depending forked sheave receiving element terminating in horizontally disposed feet 90 said top piece being provided exteriorly with a guy ring receiving element, the skirt of said top piece and said feet forming means for spar attachment, mediums securing said spar to said skirt and feet, a 95 sheave journaled within the forked element, a guy ring so mounted upon said guy ring receiving element that the spar is rotatably movable with respect thereto and a medium for retaining said guy ring in position. 100

In testimony whereof, we have hereunto signed our names in the presence of two witnesses.

EDWIN A. GASKILL.

JOSEPH FRANKLIN GASKILL.
